UNITED STATES PATENT OFFICE

ARTHUR P. PAYNE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

TUBE-FRAME-SUPPORTING CHAIN FOR AXMINSTER LOOMS

Application filed June 5, 1928. Serial No. 283,044.

This invention relates to improvements in Axminster loom chains and tube frames and it is the general object of the invention to provide a readily removable finger on the transporting chain or tube frame to cooperate with a complementarily formed attaching device on the tube frame.

In my prior Patent No. 1,493,561 I have shown a transporting chain having a plurality of fingers or tongues secured permanently thereto to cooperate with locking plungers carried by the tube frames. It occasionally happens that a tongue or finger will become broken or damaged to such an extent as to interfere with the proper operation of the tube frame, but as made according to my said patent it is rather difficult to remove and replace a damaged finger. It is a further object of my present invention to provide a tube frame supporting finger which may be applied to a chain in a ready and convenient manner to facilitate mill operation.

There are a number of Axminster looms in use at the present time having the old style chains without tongues or fingers of any kind and in order to make it possible to use these chains it is a further object of my invention to provide a form of tongue which may be applied to existent chains to the end that the latter may be retained as operating parts of the loom.

It is a more particular object of my invention to provide the tongue or finger having provision for engagement with a chain link on opposite sides thereof, the tongue or finger preferably having a pair of spaced chain link engaging elements the relative position of which may be changed slightly by the blow of a hammer or similar implement so that the finger may be fitted and held tightly to the chain link.

With these and other objects in view which will appear as the description proceeds, my invention resides in the combination and arrangement of parts hereinafter described and set forth in the claims.

In the accompanying drawings, wherein two forms of my invention are set forth,

Fig. 1 shows an end elevation of the lower portion of a pullover chain sprocket and tube

frame having the preferred form of my invention applied thereto,

Fig. 2 is an enlarged vertical section on line 2—2 of Fig. 1 showing the parts in detached position,

Fig. 3 is an end elevation looking in the direction of arrow 3, Fig. 2 showing my improved form of finger in end elevation,

Fig. 4 is a detailed horizontal section on line 4—4 of Fig. 3,

Fig. 5 is a view similar to the upper portion of Fig. 3 but showing the modified form of the invention, and

Fig. 6 is a detailed vertical section on line 6—6 of Fig. 5.

Referring particularly to Figs. 1—4 I have shown a pullover shaft 10 and a chain sprocket 11 which cooperates with the transporting chain 12. It is to be understood that there will be one sprocket and chain at each end of the loom and that the mechanism to be described hereinafter will be duplicated on both sides of the loom, and for this reason a description of the device as located at one side of the loom will suffice to cover those located at the opposite side also. The transporting chain 12 is provided with double links 13 and single links 14, the sprocket 12 ordinarily having recesses 15 located adjacent the double links 13.

The tube frame 16 may be made of a hollow metal bar rectangular in cross section and may have a bracket 17 secured thereto by means of screws 18. The bracket has an upwardly extending spool bearing portion 19 and guides the head or right hand end as viewed in Fig. 2 of a locking plunger 21. The other or left hand end of the plunger as shown in Fig. 2 is guided by a wall 22 formed as part of member 23 held to the tube frame by screws 24. Said member 23 has a wall 25 spaced from the bracket 17 to define a pocket into which projects the lower end 26 of a finger F carried by the transporting chain. The finger has an opening 27 as shown in Fig. 3 to receive the plunger head 20 and there is extending downwardly from said opening 27 a narrow slot 28.

Clutch C carries a stud 29 having a narrow vertical fin 30 which is capable of slid-

ing down through the slot 28. Said clutch also has a tube frame supporting lip 31 and a stud 32 by means of which the clutch C may be rotated on the stud 29 as an axis. The 5 stud 29 is supported by a transerrer arm 33, shown particularly in Fig. 1.

In operation, the head 20 normally projects through the bracket 17 and into the opening 27 to hold the tube frame locked relatively to the finger on the transporting 10 chain. When the tube frame is to be moved from the chain to tuft forming position, however, the clutch C will be moved inwardly so that the fin 30 thereof will push the 15 plunger backwardly to a position where it will be disengaged from the finger, after which the transerrer arm 33 can move downwardly to move the tube frame toward the fabric.

20 The matter thus far described, except the form of the finger, is substantially the same as set forth in my aforesaid patent and certain details of construction shown but not completely described herein are set forth in 25 my co-pending application Ser. No. 278,891, filed May 18, 1928.

As previously stated my present invention relates more particularly to the form of the finger F and in carrying my invention into 30 effect I provide the finger with a portion having a depending arm 41 which extends below one of the links 13. A screw 42 passes through arm 41 and the adjacent portion of the finger F, as shown clearly in Fig. 2. Said 35 screw is preferably though not necessarily threaded into the arm 41 and is held tightly in position by check nut 43. The effect of said screw is to clamp the finger and arm 41 tightly against the opposite vertical sides of 40 the link 13 to position the lower end of the finger with respect to the length of the tube frame.

In order that the position of the finger in a 45 plane perpendicular to the axis of the tube frame may be determined I provide said finger with a pair of oppositely extending ears 44 which as shown particularly in Fig. 4 may be inclined somewhat as at 45 to the body of the finger F. Said ears extend under the 50 link 13 as shown in Fig. 3 and cooperate with the U-shaped upper part of the finger to grip the chain link and position the finger.

I prefer to make the finger of pressed metal 55 such as sheet steel in which case the ears can be bent relatively to the finger so that the latter will be fitted and held tightly to the chain link 13. If desired, I may form the finger with the ears purposely a little higher than is desired so that they may be forced 60 downwardly a proper distance to effect proper fit with the link 13.

In the modified form of the invention illustrated in Figs. 5 and 6 I have shown means by which the finger may be held tightly to the 65 link 13 in such a way as to prevent improper

movement of the finger in a plane perpendicular to the axis of the tube frame. As shown particularly in Fig. 6 I strike from the upper end of the finger F' a lug 50 which is offset from the body of the modified form of finger and projects upwardly between the links 13. Another portion of the finger F' extends upwardly in a straight line from the body of the finger and is provided with an inclined surface 51 which cooperates with a collar 52 having an inclined surface 53. A screw 54 extends through the arm 50 and the upward extension of the finger F' and also the collar 52, being held tightly in position by a check nut 55. 70 75 80

The parts of the modified form of finger will be so designed that the lower edge of the screw 54 will engage the upper portion of the adjacent link 13 with the collar 52 disposed upwardly with respect to the inclined surface 51. When the screw is tightened in place the surface 53 of the collar 52 will move downwardly along the surface 51 to clamp the link 13 and finger F' together tightly. In the modified form of the invention I may 90 use ears 56 which are similar in purpose and construction to the ears 44 of the preferred form of the invention. In the modified form of the invention, however, it will ordinarily not be necessary to alter the location of the 95 ears 56 as the adjusting of the parts to effect correct fitting is brought about by the cooperation of the inclined surfaces on the finger F' and collar 52.

From the foregoing it will be seen that I 100 have provided a simple form of readily detachable and replaceable finger which has contact with the chain link at a plurality of points so that the finger is held tightly in position relatively to the transporting chain 105 links 13. It will further be seen that by removing either of the screws 42 and 54 the fingers may be removed either for repair or replacement. It will further be seen that the ears which extend under the links 13 effectively position the finger and in the case of the preferred form of the invention afford ready means for causing close fit between the fingers and the transporting chain. 110 115

Having thus described my invention it will 115 be seen that changes and modifications may be made therein by those skilled in the art without departing from the spirit and scope of the invention and I do not wish to be limited to the details herein disclosed, but what 120 I claim is:

1. In an Axminster loom, a transporting chain, a tube frame having a pocket, a finger permanently connected to the chain under normal conditions and effective to enter the 125 pocket, said finger having portions to engage opposite sides of the chain, and detachable means to hold said portions of the finger against the opposite sides of the chain.
2. In an Axminster loom, a transporting 130

- chain, a tube frame having a pocket, a finger permanently connected to the chain under normal conditions and effective to enter the pocket, said finger having portions to engage opposite sides of the chain, and detachable means to hold said portions of the finger against the opposite sides of the chain, said detachable means being independent of the chain. 5
- 10 3. In an Axminster loom, a transporting chain, a tube frame having a pocket, a finger permanently connected to the chain under normal conditions and effective to enter the pocket, said finger having a bent back portion defining two substantially parallel parts of the finger which lie on opposite sides of the chain, and means independent of the chain to clamp said parts against the chain. 15
- 15 4. In an Axminster loom, a transporting chain, a tube frame having a pocket, a finger permanently connected to the chain under normal conditions and effective to enter the pocket, said finger having one end thereof bent back on itself to define a pair of substantially parallel spaced portions between which extends the chain, and detachable means independent of the chain extending through said portions and clamping the same tightly to the chain. 20
- 20 5. In an Axminster loom, a transporting chain having a double link formed of two members, a tube frame having a pocket, a finger permanently connected to the chain under normal conditions and effective to enter the pocket of the tube frame and having a portion extending between the members of the double link and detachably but rigidly secured to one of said members. 25
- 25 6. In an Axminster loom, a transporting chain having a double link formed of two members, a tube frame having a pocket, a finger permanently connected to the chain under normal conditions and having one portion to enter the pocket of the tube frame and having another portion to extend between the members of the double link, and means to detachably but rigidly secure said fingers to one of the members of the link. 30
- 30 7. In an Axminster loom, a transporting chain having a double link formed of two members, a tube frame having a pocket, a finger permanently connected to the chain under normal conditions and having one portion to enter the pocket of the tube frame and having another portion to extend between the members of the double link, and means to detachably but rigidly secure said finger to one of the members of the link, said means being independent of the chain. 35
- 35 8. In an Axminster loom, a transporting chain having a double link formed of two members, a tube frame having a pocket, a finger having one portion to enter the pocket of the tube frame and having another portion bent back on itself to define a pair of spaced substantially parallel parts, one of said parts extending between the members of the double link, and detachable means passing through both of said parts to hold said finger rigidly to the double link. 40
- 40 9. In an Axminster loom, a transporting chain, a tube frame having a pocket, a finger permanently connected to the chain under normal conditions and effective to enter the pocket, said finger having a portion for attachment with the chain, said portion including a pair of spaced ears to extend from the finger and engage one side of the chain, said finger including a bent-over portion to extend around the chain and engage that side of the chain opposite the ears, and detachable means extending through the bent-over portion of the finger and independent of the chain to hold said finger to the chain. 45
- 45 10. In an Axminster loom, a transporting chain, a tube frame having a pocket, a finger permanently connected to the chain under normal conditions and effective to enter the pocket, said finger having a pair of oppositely extending ears to lie under a portion of the transporting chain, said finger having another part to extend over the same portion of the chain, and means to hold the finger detachably to the chain, said part which extends over the chain, and the ears which extend under the chain, serving to position the finger relatively to the chain. 50
- 50 11. In an Axminster loom, a transporting chain, a tube frame having a pocket, a finger permanently connected to the chain under normal conditions and effective to enter the pocket, said finger having a pair of oppositely extending ears to lie under a portion of the transporting chain, said finger having another portion to extend over the same portion of the chain, and means to hold the finger detachably to the chain, said portion which extends over the chain and the ears which extend under the chain serving to position the finger relatively to the chain, said ears being bent out of the plane of the finger to extend under the chain. 55
- 55 12. In an Axminster loom, a transporting chain having a link with substantially vertical parallel walls, a tube frame having a pocket, a finger permanently connected to the chain under normal conditions and having a portion to enter the pocket and having another portion to cooperate with the link, said other portion having spaced parallel parts which lie on opposite sides of the link and on different sides of the parallel walls of said link, ears formed integrally with the finger extending from one of the parts of the finger and being bent under the link to engage the latter, and detachable means to hold the finger to the link. 60
- 60 13. A finger for an Axminster loom transporting chain to cooperate with a tube frame having a pocket, said finger permanently con- 65

nected to the chain under normal conditions and having one portion to enter a pocket and cooperate therewith to support the tube frame and having another portion formed with substantially parallel spaced parts to engage opposite sides of the chain.

14. A finger for an Axminster loom transporting chain to cooperate with a tube frame having a pocket, said finger permanently connected to the chain under normal conditions and having one portion to enter the pocket and cooperate therewith to support the tube frame and having another portion formed with substantially parallel spaced parts to engage opposite sides of the chain, and a clamping member extending between said parts to clamp the latter against the chain.

15. A finger for an Axminster loom transporting chain to cooperate with a tube frame having a pocket, said finger permanently connected to the chain under normal conditions and having one portion to enter the pocket and cooperate therewith to support the tube frame and having another portion formed with substantially parallel spaced parts to engage opposite sides of the chain, said finger having integral therewith oppositely extending fingers to engage one side of the chain to position the finger relatively to the chain.

16. A finger for an Axminster loom transporting chain to cooperate with a tube frame having a pocket, said finger permanently connected to the chain under normal conditions and having one portion to enter the pocket and cooperate therewith to support the tube frame and having another portion formed with substantially parallel spaced parts to engage opposite sides of the chain, said finger having integral therewith oppositely extending fingers to engage one side of the chain to position the finger relatively to the chain, said fingers being bent out of the plane of the finger to lie under the chain.

17. A finger for an Axminster loom transporting chain to cooperate with a tube frame having a pocket, said finger permanently connected to the chain under normal conditions and having one portion to enter the pocket and cooperate therewith to support the tube frame and having another portion formed with substantially parallel spaced parts to engage opposite sides of the chain, that portion of the finger which engages the chain being bent back on itself to define said parallel parts.

In testimony whereof I have hereunto affixed my signature.

ARTHUR P. PAIN.
